UNITED STATES PATENT OFFICE

WILLIAM T. HERRICK, OF TULSA, OKLAHOMA

CIGARETTE AND CIGAR EXTINGUISHER

Application filed May 15, 1928. Serial No. 277,859.

The present invention pertains to improvements in a device for extinguishing lighted cigarettes and cigars and briefly consists of a receptacle adapted to contain water, a coiled 5 spring arranged within the container for supporting a discular member of foraminous material.

An important object of this invention is in the provision of a device of this nature which 10 will efficiently extinguish lighted cigarettes or cigars without breaking or crumbling the same, so that if desired, the same may be again smoked.

Another object resides in providing such 15 a device capable of being manufactured at a very low cost, and which because of its unique construction will be durable and efficient in operation.

Still another object is realized by the fact 20 that the discular member associated with the device is constructed of foraminous material, so that the touching of the lighted article against the same will permit trash particles to pass therethrough and into the water compartment.

Other novel advantages and objects of the 25 invention will become apparent as the same is better understood from the following specification and claim.

In the drawing:

Figure 1 represents a top plan view of the 30 device, and

Figure 2 represents a side elevation of the 35 same and showing a portion thereof broken away to disclose the tensional means for supporting the foraminous discs.

Now for a more detailed description of this 40 invention, reference is made to the drawings, wherein like numerals designate like parts.

In carrying out the purpose of the present 45 invention, there is provided an open top receptacle 1, constructed of suitable material, such as glass or metal. This receptacle may also be constructed of any shape desired, although it is believed that the cylindrical construction disclosed in the drawing is the most practical.

Arranged within the receptacle 1 is a coiled 50 spring 2, which is constructed of several convolutions of relatively fine spring material.

The convolutions are of substantially wide spaced relation and is otherwise constructed to permit the compression thereof with but slight effort. The lower portion of the spring 3 is disposed slightly obliquely with respect 55 to the disposition of the convolutions, so that the springs may be supported in a substantially vertical position. The upper end portion of the spring is likewise disposed for engaging the bottom side of a foraminous disc 5. 60 The disc 5 is slightly less in diameter than the inner diameter of the receptacle 1, so that the same is freely slideable therein. This disc 5 is provided with a depending peripheral skirt 6, which is adapted to guide the sliding movement of the disc 5 and to prevent the assuming 65 of any disposition thereof aside from a substantially horizontal working position.

As before stated, it is desired that this ring 70 be of very weak tension, so that by engaging the lighted end of a cigar or cigarette against the top surface of the foraminous disc 5, the disc may be readily depressed for permitting the passage of water through the mesh construction thereof to extinguish the lighted 75 article.

It is to be understood that while I have 80 illustrated in the drawings the preferred embodiment of this invention, slight changes, such as in the shape of the details, kinds of materials, or any ornamental designs may be resorted to, without departing from the spirit of this invention or the scope of the appended claim.

Having thus described this invention, what 85 is claimed as new is:

In a cigar or cigarette extinguishing device comprising a container adapted to contain a liquid, a porous member slideable within the container, said member being provided 90 with a depending peripheral skirt adapted to guide said member within the container, and a spring member arranged within the container and adapted to tensionally support the porous member, said spring having its 95 upper end disposed within the confines of the said skirt.

In testimony whereof I affix my signature.

WILLIAM T. HERRICK. 100
